NURSERY TAG MOUNTING DEVICE
Alfred P. Brill, P.O. Box 35, Lake Shore Drive,
Canal Point, Fla. 33438
Filed Jan. 20, 1966, Ser. No. 521,859
11 Claims. (Cl. 29—21.1)

The instant invention is broadly concerned with the mounting of identifying tags on rod-like objects, and more directly relates to a device or tool which, from a mounted roll of tag material, advances a predetermined portion of the material into encircling relationship about a rod-like member, punch locks the encircling material and severs a length of material sufficiently greater than the encircling portion thereof so as to enable the provision of an identifying title or the like thereon.

While the device of the instant invention can be used to tag any relatively slender rod-like member, it is contemplated that it find particular utilization in tagging nursery stock. Thus, it is a particularly significant object of the instant invention to provide a device which is compact, easy to carry and operate, and contains its own supply of tag-forming material.

Another significant object of the instant invention is to provide a device which provides trouble-free operation.

Basically, the device of the instant invention is to include a tape advancing unit for progressively moving a strip of tape from a supply roll to and about a branch cradled within the forward portion of the device, means for effecting a punch locking of the tape about the branch, and means for severing a portion of the secured tape of a length sufficient so as to enable the provision of suitable identification marks thereon.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the device comprising the instant invention;

FIGURE 2 is an enlarged top plan view of the device;

FIGURE 3 is a vertical cross-sectional view taken through the device;

FIGURE 4 is a transverse cross-sectional view taken substantially on a plane passing along line 4—4 in FIGURE 3;

FIGURE 5 is a view similar to FIGURE 3 and illustrating the tape in its advanced limb-encircling position;

FIGURE 6 is a view similar to FIGURES 3 and 5 illustrating the manner in which the tape is cut and locked to the limb;

FIGURE 7 is an enlarged cross-sectional view taken substantially on line 7—7 in FIGURE 3; and

FIGURE 8 is a partial perspective view illustrating the type of mounted tag produced by a manipulation of the device of the instant invention.

Referring now more specifically to the drawings, reference numeral 10 is used to generally designate the nursery tag mounting device comprising the instant invention. The device 10 is constructed on an elongated basic frame 12 including a hollow rectangular rear portion 14 and an upwardly opening forward channel-shaped portion 16 defined by an integral continuation of the bottom of the

2

tubular portion 14 and approximately one-half of each of the side walls thereof.

Affixed to the opposite sides of the tubular portion 14 adjacent the rear end thereof are a pair of upwardly and rearwardly enlarged arcuate mounting plates 18 which receive a removable mounting pin 20 therebetween, this pin in turn mounting a roll or coil of the material, generally thin strip aluminum, from which the individual tags 22 are to be formed. The elongated strip of severable material has been indicated by reference numeral 24.

The strip 24 is fed off the roll or coil and through the tubular portion 14 which is provided with an elongated internal guiding block 26. This guide block 26, as will be appreciated from the cross-sectional views, has a tapered lower guiding surface 28 converging forwardly toward the bottom or base of the elongated frame member 12. In this manner, it will be noted that a relatively wide mouth 30 is provided so as to facilitate the insertion of the leading end of the strip 24 with the guide channel progressively decreasing toward the base along which the strip 24 is to slide so as to provide for a flat positioning of the strip 24 on the bottom of the frame member 12. Further, it will be noted that the rear lower corner 32 of the guiding block 26 is rounded so as to form a smooth surface over which the strip 24 can easily pass.

As the strip 24 passes into the channel portion 16 of the frame member 12, it passes under a block 34 which extends between the side walls of the channel portion 16 and acts so as to further guide the strip 24.

The base of the frame member 12 is rigidified along the length thereof by an elongated rectangular bar 36 fixed thereto in any suitable manner such as by welding. This reinforcing bar 36 terminates at the forward end of the channel-shaped portion 16. As the strip 24 of the tag-forming material moves forwardly, in a manner which shall be described presently, the leading end thereof moves out of the forward portion 16 and continues along an upwardly and rearwardly curving arcuate path defined by the curved forward portion 38 of a forming member or shoe 40 bolted to the lower face of the reinforcing bar 36 in a manner so as to position the arcuate portion 38 thereof forwardly of the point at which the strip 24 discharges from the frame member 12, this being clearly apparent from the drawings. It will be noted that the outer reversely directed end 42 of the reversely curving portion 38 is spaced from the remainder of the shoe for a sufficient distance so as to allow the portion 38 to be easily hooked about a branch or other rod-like member 44.

Affixed to opposite sides of the channel-shaped portion 16 of the frame member 12 by any suitable fastening means such as bolts, rivets or welding, are a pair of spaced vertical side panels or walls 46. With reference to FIGURE 1 in particular, it will be noted that the upper edges of these side panels 46 are coplanar and converge downwardly and forwardly generally toward the arcuate portion 38 of the shoe 40, terminating in a vertical edge at substantially the forward end of the frame member 12 with the lower portions of these panels continuing forwardly so as to engage the shoe 40 along the opposite edges thereof to a point approaching the forward extremity of the arcuate portion 38, thereby effectively stabilizing and rigidifying this portion while not interfering with the access thereto in light of the relatively short height of these forward projecting portions.

The advance of the tape 24 is effected by an advancing block 48 having a rubber gripping face thereon. This block 48 rests on top of the upper surface of the strip 24 between the side panels 46 and is controlled through a pair of rigid elongated links 50 pivotally pinned, as by pin 52, to the opposite sides of the block 48 through elongated guide slots 53 in the opposite side panels 46 paralleling the base of the frame member 12 above the short side walls of the channel portion 16. The elongated links 50 are in turn pivotally connected, at their upper ends, by pin 55 to a pair of elongated generally vertical links 54 which straddle and are pivotally secured to the opposite sides of the frame member 12, as at 56. The lower ends of the elongated links 54 are pivotally engaged, through short connecting links 58, to the upper end of a movable finger-receiving handgrip 60 which in turn has the lower end thereof pivotally engaged, as at 62, with the lower end of a fixed handle portion 64 rigid with the base-reinforcing bar 36 and depending therefrom. It will be noted that the inner edge of the movable handle portion 60 is recessed as at 66 so as to be telescopically received over the forward edge of the fixed handle portion 64. Through this structure, it will be appreciated that as the handle portion 60 is moved toward the fixed handle portion 64, the block 48, through the links 50, 54 and 58, will bear against the strip 24 and urge the strip along a sliding path on the base of the frame member 12, the block 48 being guided by the elongated opposed slots 53 through which the pivot pin 52 passes. It is contemplated that two to three squeezes on the handle be sufficient so as to advance the strip 24 forwardly about the arcuate shoe portion 38 and into the position generally indicated in FIGURE 5 about the branch 44.

The tag 22 is formed from the advanced portion of the strip 24 by forming a lock tab within the material itself utilizing the portions thereof overlapped rearward of the twig 44 and severing the strip at a point rearward of the tab lock sufficient so as to provide space for the provision of suitable identification thereon. The forming of the lock tab 68 is effected by an elongated punch 70. The punch or punch member 70 includes an elongated cylindrical rod 72, a rectangular shaft portion 74 fixed rigid with the forward end of the rod 72, and a punch blade 76 fixed to the forward end of the shaft portion 74. The rod portion 72 is received centrally through an enlarged rectangular sleeve 78 fixed between the vertical side panels 46 along the rear portion of the upper edges thereof and following the angle of the inclined upper edges of these side walls 46. The rear end 80 of the sleeve 78 is partially closed, having only a concentric aperture therethrough sufficient so as to slidably receive the rod 70. An enlarged collar 82 is fixed to the rod 72 within the sleeve 78 and defines an abutment against which an expanded coil compression spring 84 bears, the rear end of the spring 84 bearing against the partially closed end 80 of the sleeve 78, thereby biasing the punch or punch member 70 forwardly.

The rectangular shaft portion 74 is positioned within and slidably guided by a correspondingly shaped rectangular passage 86 within a sleeve 88 mounted, through mounting enlargements or blocks 90, between the side walls or panels 46 in alignment with the sleeve 78. It will be appreciated that the mating nature of the rectangular shaft portion 74 and the rectangular passage 86 eliminates any tendency for or possibility of the punch 70 rotating out of position.

The punch blade 76 is rectangular in cross section and slightly narrower than the shaft portion 74. In addition, in order to form the desired curled or coiled lock tab 68 as illustrated in FIGURE 6, the lower edge 92 of the blade 76 is beveled forwardly so as to define a piercing point or edge 94. This piercing edge 94, in conjunction with the beveled lower surface 92, is introduced below the leading end 42 of the arcuate portion 38 of the shoe 40

and pierces the overlying layers of the sheet material 24, the arcuate portion 38 of the shoe 40 of course including a slightly elongated rectangular opening 96 therethrough which allows for the passage of the blade 76 so as to effect the desired tab folding. In actual operation, the pointed edge 94 will pierce the double layer of sheet material or tape and continue forwardly through the rectangular aperture 96 while the beveled lower edge 92 of the blade shears the opposite sides of the tab from the main sheet, cooperating with the vertical sides of the opening 96, and rolls the tab into a tight coil of material against the lower edge of the opening 96, as indicated by reference numeral 68 in FIGURE 6. In this manner, the two layers of the sheet material are fixedly interlocked into a loop-defining relationship which encircles the limb 44.

The punch 70 is cocked by retracting it against the biasing force of the spring 84 through the rear mounted grip 98 which in turn is provided with a cushion 100 just forward thereof for cushioning the engagement with the partially closed rear end 80 of the sleeve 78. The selective maintaining of the punch or punch member 70 in its retracted or cocked position is effected through the engagement of a lug 102 within a notch 104 in the lower surface of the rod section 72 just rearward of the shaft portion 74.

The lug 102 is bolted, through a laterally directed leg 106, to a sleeve member 108 which slidably receives the elongated trigger rod 110 and in turn pivotally mounts the trigger rod 110 between and to the opposite wall panels 46 by oppositely directed pivot pins 112. The forward end of the trigger rod 110, having a beveled lower surface as does the sleeve 108 so as to allow for free movement of the pusher block 48, is biased downwardly to a position just clearing the block 48 by a coiled compression spring 114 engaged about a central stub 116 on the block 34 and projecting thereabove for engagement of the upper end thereof within a spring-retaining recess 118 on a block 120. This block 120 in turn slidably receives the rod 110 rearward of the pivot point thereof. Thus, it will be appreciated that upon a downward pivoting of the rear end of the trigger rod 110 against the biasing force of the spring 114, the lug 102 will disengage from the notch 104 and allow a forward pressurized driving of the punching member 70. The depression of the trigger rod 110 will of course take place after a sufficient amount of the tape 24 has been advanced so as to encircle the limb or branch 44.

It is also contemplated that the tag portion 22 of the tape be simultaneously severed along with the formation of the locking tab 68. Accordingly, a blade mounting member 122 is pivotally mounted between the walls 46 forward of the forward end of the trigger rod 110. This mounting member 122 includes a portion thereof rearward of the pivot point 124 which overlies the forward end of the rod 110 and which is biased downwardly thereagainst by leaf spring 126 engaged between the rear portion of the member 122 and a superjacent mounting block 90 for the sleeve 88. The cutting blade 128 is itself mounted on the forward end of the member 122 forward of the pivot point 124 in any suitable manner so as to depend therebelow for cutting engagement with the tape 24 as the member 122 pivots through a raising of the rear end thereof by the raising forward end of the trigger rod 110 when effecting a withdrawal of the lug 102. Once the trigger rod 110 is released, this being subsequent to the forming of the locking tab 68 and the severing of the tape by the blade 128, the spring 114 returns the rod 110 to its original position for subsequent engagement of the lug 102 within the notch 104 upon a cocking of the punch member 70, and the spring 126 simultaneously returns the blade-carrying member 122

In order to provide for a return of the movable handle section 60 after each squeeze thereon, it will be noted that a coiled compression spring 130 is provided about

the trigger rod 110 and engaged between the block 120 and a pair of oppositely directed stubs 132 fixed to the rod 110 at a point therealong contemplated so as to engage against a pair of wear plates 134 fixed to the forward edge of each of the substantially vertical links 54. In this manner the links 54, above the pivot point 56, are biased rearwardly so as to effect a forward biasing of the movable handle portion 60. The block 120 can be retained in position against the force of the spring 130 either by the lateral stability of the spring 114 or by guide pins, not shown, received through arcuate generally vertical slots in the opposed side panels 46.

It will be noted that inasmuch as, in the at-rest position, the links 54 are orientated substantially vertically, the forward movement of the upper ends thereof pivoted to the links 50 will be at a slight downward angle so as to tend to force the pushing or advancing block 48 downwardly against the tape 24 into frictional engagement therewith. By the same token, the rearward movement of the links 50 and 54, under the influence of the biasing spring 130, is such so as to cause a slight raising of the block 48 so as to not produce a rearward movement of the tape 24, the height of the guide slots 53 being sufficient to accommodate this slight vertical play or movement of the block 48. With regard to the rearward movement of the block 48, as will be appreciated from FIGURES 3 and 6, this movement can be limited by engagement of the block 48 against the mounting block 34, or by engagement of the pivot pin 52 with the rear limit of the slots 53. Further, although not specifically set forth supra, it will be noted that the mounting block 34, referring to FIGURE 7, can be fixed into position by a pair of oppositely directed bolts 136 extending inwardly through the opposed side panels 46 and channel portion walls.

In operation, after loading a coil of tag-forming tape material 24 on the device and feeding the leading end thereof through the frame member 12 and along the base thereof to a point just forward of the advancing block 48, the device is manipulated so as to position a rod-like member, such as for example a plant or tree branch or stem 44, within the reversely curving hook-like portion 38. Next, the movable handle portion 60 is manipulated approximately two times so as to advance the tape 24 into a looped configuration about the twig 44 as illustrated in FIGURE 5. Next, the rear end of the trigger rod 110 is depressed so as to withdraw the lug 102 and release the punch 70. Upon release, the punch member 70 is driven forward with the punch blade 76 piercing the overlapped layers of the tape and forming a tab lock therein so as to lock the forward portion of the tape to the twig 44. At the same time, the member 122 is pivoted so as to effect, through the cutting blade 128, a severing of the tape 24 rearward of the looped portion thereof, thereby providing a length upon which the identification of the rod-like member 44 can be imprinted in any suitable manner. Once the tape has been severed by the cutting blade 128, the trigger rod 110 is released with this rod 110, the cutting blade mounting member 122, and the movable handle portion 60 being automatically biased into their at-rest positions. The punch member 70 is manually retracted through the gripping handle 98. Upon retraction of the punch member 70, the device 10 is simply manipulated so as to disengage the tagged branch 44 from the hooked portion 38, thus leaving the device free for the hanging of another tag.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A strip tag mounting device comprising a frame, means on said frame for selectively advancing a predetermined amount of strip material, means on said frame for forming the advanced strip material into an object encircling shape with a leading portion of the strip material overlying a portion of the strip material rearward thereof, means on said frame for fixing the overlying portions of material to each other in their object encircling shape, and means on said frame for severing the strip material at a predetermined distance from the encircling portion.
2. The device of claim 1 including means on said frame for mounting a selectively dispensable supply of strip material.
3. The device of claim 2 wherein said frame includes an elongated strip material receiving and guiding base extending from the supply mounting means to the forming means, said forming means comprising a reversely curving continuation of the material guiding base, the extreme end of which overlies and is spaced from the guiding base.
4. The device of claim 3 wherein said material fixing means comprises a lock forming material piercing and bending member selectively introduced into said curving continuation through the space between the extreme end of the curving continuation and the guiding base, said continuation having a forming aperture defined therein for reception of and cooperation with the lock forming member.
5. The device of claim 4 including means resiliently biasing said lock forming member toward the curving continuation, restraining means engaged with said lock forming member and preventing movement thereof under the influence of the biasing means, and release means for selectively releasing said restraining means, said release means being operatively associated with said material severing means for effecting a substantial simultaneous release of the restraining means and actuation of the material severing means.
6. The device of claim 5 wherein the strip material advancing means includes an advancing member overlying the material receiving base, and means engaged with said advancing member for selectively moving said advancing member downwardly toward said base and forwardly therealong.
7. The device of claim 6 including means resiliently biasing said advancing member rearwardly along said base.
8. The device of claim 7 wherein said means for selectively moving said advancing member comprises at least one elongated rigid link pivotally engaged with said advancing member and projecting rearwardly and upwardly therefrom, a second rigid elongated link pivotally engaged with the upper end of said first link and depending therefrom below said frame, means pivotally engaging an intermediate portion of said second link with said frame, and handle means associated with the lower end of said second link for effecting a pivotal movement thereof.
9. The device of claim 3 wherein the strip material advancing means includes an advancing member overlying the material receiving base, and means engaged with said advancing member for selectively moving said advancing member downwardly toward said base and forwardly therealong.
10. The device of claim 9 wherein said means for selectively moving said advancing member comprises at least one elongated rigid link pivotally engaged with said advancing member and projecting rearwardly and upwardly therefrom, a second rigid elongated link pivotally engaged with the upper end of said first link and depending therefrom below said frame, means pivotally engaging an intermediate portion of said second link with said

frame, and handle means associated with the lower end of said second link for effecting a pivotal movement thereof.

11. The device of claim 5 wherein said release means comprises an elongated rod overlying the frame base, means pivotally mounting said rod at an intermediate point thereof for movement of the opposite ends of the rod in opposite directions in a plane toward and away from said base, said material severing means including a pivotally mounted member having one end engaged

with and controlled by a first end of said pivotally mounted rod, a severing blade being mounted on the other end of the pivotally mounted member whereby a pivotal movement of the blade will be effected by a pivotal movement of the second end of the pivotally mounted rod.
